(57) **CLAIM**

The ornamental design for a lounge, as shown and described.

DESCRIPTION

FIG. 1 is a front perspective view of a lounge according to a first embodiment of our new design;

FIG. 2 is a front view thereof;

FIG. 3 is a rear view thereof;

FIG. 4 is a left side view thereof;

FIG. 5 is a right side view thereof; and

FIG. 6 is a top view thereof;

FIG. 7 is a front perspective view of a lounge according to a second embodiment of our new design;

FIG. 8 is a front view thereof;

FIG. 9 is a rear view thereof;

FIG. 10 is a left side view thereof;

FIG. 11 is a right side view thereof; and

FIG. 12 is a top view thereof;

FIG. 13 is a front perspective view of a lounge according to a third embodiment of our new design;

FIG. 14 is a front view thereof;

FIG. 15 is a rear view thereof;

FIG. 16 is a left side view thereof;

FIG. 17 is a right side view thereof; and,

FIG. 18 is a top view thereof.
